US0D1062629S

(12) **United States Design Patent** (10) Patent No.: **US D1,062,629 S**
(45) Date of Patent: ** Feb. 18, 2025

(54) **WIRELESS CHARGER**

(71) Applicant: **Weiyu (Shenzhen) Technology Co., Ltd.**, Shenzhen (CN)

(72) Inventor: **Yaohua Xie**, Guangdong (CN)

(**) Term: **15 Years**

(21) Appl. No.: **35/517,465**

(22) Filed: **May 10, 2023**

(80) **Hague Agreement Data**

Int. Filing Date: **May 10, 2023**

Int. Reg. No.: **DM/229237**

Int. Reg. Date: **May 10, 2023**

Int. Reg. Pub. Date: **Jun. 9, 2023**

(30) **Foreign Application Priority Data**

Mar. 24, 2023 (CN) 202330149104.9

(51) **LOC (15) Cl.** **13-02**

(52) **U.S. Cl.**

USPC **D13/108**

(58) **Field of Classification Search**

USPC D13/108; D14/253, 434

CPC Y02E 60/10

Primary Examiner — Leanne Was-Englehart

Assistant Examiner — Alison Davis

(57) **CLAIM**

The ornamental design for a wireless charger as shown and described.

DESCRIPTION

1. Wireless charger

1.1 : Front

1.2: Back

1.3 : Left

1.4 : Right

1.5:Top

1.6: Bottom

1.7: Perspective

1.8: Perspective

1.1 is a front view of a wireless charger showing my new design; 1.2 is a back view thereof; 1.3 is a left view thereof; 1.4 is a right view thereof; 1.5 is a top view thereof; 1.6 is a bottom view thereof; 1.7 is a perspective view thereof; and 1.8 is another perspective view thereof.

The broken lines shown in the figures are for the purpose of illustrating portions of the wireless charger and form no part of the claimed design.

1 Claim, 8 Drawing Sheets
